RACK FOR SUPPORTING MERCHANDISING DISPLAY SHELVES AND BASKETS OR THE LIKE

Willy Tissot, 21 Petit-Chene, Lausanne, Switzerland

Filed June 16, 1959, Ser. No. 56,375

Term of patent 14 years

(Cl. D80—10)

Fig. 1 is a front perspective view of a rack for supporting merchandising display shelves and baskets or the like, showing my new design;

Fig. 2 is a side elevation thereof; and

Fig. 3 is an enlarged fragmentary view partially in cross-section showing the configuration of one of the frame elements.

The broken-line representations in Figs. 1 and 3 are for purposes of illustration only.

I claim:

The ornamental design for a rack for supporting merchandising display shelves and baskets or the like, as shown and described.
